CLAIM

The ornamental design for an arrow shaft gripper, as shown and described.

DESCRIPTION

FIG. 1 is a perspective right end view of an arrow shaft gripper showing a first embodiment of my new design;
FIG. 2 is a perspective left end view thereof;
FIG. 3 is a top plan view thereof;
FIG. 4 is a bottom plan view thereof;
FIG. 5 is a perspective right end view of an arrow shaft gripper showing a second embodiment of my new design;
FIG. 6 is a perspective left end view thereof;
FIG. 7 is a top plan view thereof; and,
FIG. 8 is a bottom plan view thereof.
